UNITED STATES PATENT OFFICE.

JOHN A. ALBERTONI AND ENRICO TROPEANO, OF AKRON, OHIO.

CLASP.

No. 931,023.

Specification of Letters Patent. Patented Aug. 17, 1909.

Application filed September 16, 1908. Serial No. 453,328.

To all whom it may concern:

Be it known that we, JOHN A. ALBERTONI and ENRICO TROPEANO, citizens of the United States, residing at Akron, in the county of Summit and State of Ohio, have invented 5 certain new and useful Improvements in Clasps, of which the following is a specification.

This invention relates to improvements in 10 clasps, and the object is to provide a simple and convenient device by means of which one article may be readily and securely attached to another, as for instance, a purse or napkin to the person of the owner or user.

15 With the above object in view the invention consists in the novel features of construction hereinafter fully described, particularly pointed out in the claims and clearly illustrated by the accompanying 20 drawing, in which—

Figure 1 is a side elevation, enlarged, of a clasp constructed in accordance with our invention, the parts being shown in unlocked or unclasped position; Fig. 2, a side elevation 25 showing the same locked or clasped, and Fig. 3, a perspective view with the locking-member removed.

Referring now more particularly to the drawing, the numeral 1 designates the body 30 of the clasp comprising a substantially U-shaped plate, one of the legs of which is formed intermediately of its ends with an elongated slot 2. Suitably secured at one end to the leg containing the slot 2, is a 35 spring plate 3, the free end of which is bent to extend substantially parallel with the leg to which it is attached. Formed in the free end of this spring-member is a perforation 4 to receive a locking-member which fits 40 loosely therein, said member consisting of a head or button 5 carrying a pointed pin 6 formed intermediately of its ends with laterally-extending lugs or projections 7. The slot 2 is of sufficient extent to permit the 45 lugs of the locking-member to pass therethrough when they are turned in line with the said slot. For holding the locking-member with its lugs turned cross-wise of the slot 2, the under side of the free end of the 50 spring-member is formed with grooves or depressions 4' to receive said lugs. The button with its pin is carried by the spring-plate and is normally in the position shown in Fig. 1.

55 In use the device may be operated in

several different ways. The legs of the U-shaped body may straddle the material of one of the articles, while the other article may be placed between the leg of said body and the spring-plate, the pin being passed 60 through both articles and locked by turning the lugs or projections thereof cross-wise of the slot until they rest in the depressions or grooves 4'. Or the clasp may be attached to a garment, and another garment or article 65 attached by inserting or buttoning on the head or button 5. For instance, these clasps might be used instead of buttons on the waistband of trousers and the tabs of the suspenders inserted on the buttons 5. 70

The U-shaped plate and the locking-pin and button might be used solely for one article and a spiral device 8 attached to one of the legs of the plate for securing the device to the other article. 75

Having thus fully described our invention what we claim as new and desire to secure by Letters Patent of the United States, is:

1. A device of the character described comprising a plate having an elongated slot 80 formed therein, a spring member carried by said plate, and a locking-member loosely carried by the free end of said spring-member, said locking-member comprising a head and a pin provided with laterally-extending 85 projections adapted to be turned cross-wise of said slot.

2. A device of the character described comprising a substantially U-shaped body portion having an elongated slot formed in 90 one of the legs thereof, a spring-plate secured at one end to the leg having the slot, and a locking-member loosely carried by the free end of the spring-plate comprising a head and a pin having laterally-extending 95 projections adapted to be turned cross-wise of the slot.

3. A device of the character described comprising a body having spaced members, one of which is formed with an elongated 100 slot, a spring-member carried by the body and movable at one end to and from the latter, and a locking-member comprising a head carrying a pin formed with a laterally-extending projection adapted to be turned 105 cross-wise of the slot, said locking-member being loosely carried by the movable end of the spring-member.

4. A device of the character described comprising a substantially U-shaped body 110

portion having an elongated slot formed in one of the legs thereof, a spring-plate secured at one end to the leg having the slot and formed in its under side at its free end with 5 grooves extending transversely thereof, and a locking-member loosely carried by the free end of the spring-plate comprising a head and a pin having laterally-extending projections adapted to be turned cross-wise of the

slot and to rest in said grooves of the spring- 10 plate.

In testimony whereof we affix our signatures, in presence of two witnesses.

JOHN A. ALBERTONI.
ENRICO TROPEANO.
